G. P. BRAND.
PNEUMATIC ACTION FOR PIANO PLAYERS, &c.
APPLICATION FILED MAR. 12, 1910.

Patented Aug. 27, 1912.

Fig. 1.

UNITED STATES PATENT OFFICE.

GEORGE P. BRAND, OF NEW YORK, N. Y.

PNEUMATIC ACTION FOR PIANO-PLAYERS, &c.

1,036,956.

Specification of Letters Patent. Patented Aug. 27, 1912.

Application filed March 12, 1910. Serial No. 548,987.

To all whom it may concern:

Be it known that I, GEORGE P. BRAND, a citizen of the United States of America, and resident of New York, in the county of New York and State of New York, have invented certain new and useful Improvements in Pneumatic Actions for Piano-Players, &c., of which the following is a specification.

This invention relates to certain new and useful improvements in pneumatic actions for piano players and the like and it has for its objects among others to provide means facilitating the repairs as well as the manufacture of the parts. I provide separate units detachably mounted so that each one may be readily removed without disturbing the other and replaced after being repaired, or a new one substituted. Each unit is complete in itself and is fixedly held in place and to the adjacent unit by the detachable securing means. Each unit in itself embodies novel features.

Other objects and advantages of the invention will hereinafter appear and the novel features thereof will be particularly pointed out in the appended claims.

The invention is clearly illustrated in the accompanying drawings, which, with the numerals of reference marked thereon, form a part of this specification, and in which—

Figure 1 is a perspective view showing the application of the present invention. Fig. 2 is an enlarged vertical section on the line 2—2 of Fig. 1.

Like numerals of reference indicate like parts in the different views.

Referring to the drawings, 1 designates a series of pneumatics of known construction secured, preferably by glue, to the under face of the tension chest 2 which, in practice, is of sufficient length to extend the whole width of the piano and serves for all of the pneumatics and the units or valve chests soon to be described. The valve chests are not connected to the pneumatics but are supported over the same, a small space 3 connected with the atmosphere being provided between the under faces of the valve chests and the stationary members of the pneumatics, as seen clearly in Fig. 2. These valve chests or units are detachably secured to the tension chest 2, so as to be readily removed therefrom. An efficient form of means for this purpose is seen clearly in Fig. 1, wherein it will be seen that the vertical wall 4 of the tension chest 2 is

provided with openings 5 in which are received the screw-threaded bolts 6. Each valve chest 7 is shown as provided with a shoulder 8 upon each side, and in each space 9 between the valve chests provided by such shoulders there is a plate 10 which bears against said shoulders and through which passes the end of the screw rod 6, which latter receives a nut 11. When the parts are assembled, the valve boxes are placed in position, as indicated, the plates applied, then the bolts are passed through the openings in the plates and engaged in the holes 5 in the vertical wall of the tension chests and the nuts 11 then applied to the outer ends of the bolts and turned up until the parts are made rigid. Each plate thus assists in holding two adjacent valve chests in position. Removal of the nut 11 and plate upon each side of a valve chest permits of removal of that chest for repairs or other purposes and the immediate substitution of another, it being understood that all these units are interchangeable, it being designed to make them automatically by machinery.

The chamber 12 of the tension chest extends throughout the length thereof and is designed to be connected with the exhaust mechanism of the piano player in any of the well-known ways. The wall 2 thereof, as seen clearly in both views, is practically solid except for the following passages.

13 is a lateral passage connecting the chamber 12 with a coincident passage 14 and the independent lateral passage 15 which connects with the vertical passage 16, which latter is designed to communicate with the interior of the pneumatic 1 through the vertical passage 17 in the fixed member of said pneumatic. It will be understood that there is a passage 13 as well as a passage 15 and 16 for each valve chest.

Each unit or valve chest comprises a primary tension chamber 18 and 19, see Fig. 2. Within the chamber 19 is a diaphragm 20 forming the diaphragm chamber 21.

22 is a tube communicating with the diaphragm chamber 21 and designed to extend to the tracker bar, not shown. Mounted for movement in an opening 23 in the partition 24 in the tension chamber is a valve stem 25 carrying at one end the block or abutment 26 in contact with the diaphragm 20 and its other end designed to engage a valve 27 carried by the stem 28 movable through

an opening in the upper wall of the valve chest and carrying a valve 29 outside said chest, as seen in both views.

30 is a port or passage in the partition 24 affording communication between the chambers 18 and 19, as will be readily understood upon reference to said Fig. 2.

31 is a diaphragm chamber, 32 being the diaphragm (carried by either of the members 24 or 52, preferably by the member 24), 33 the diaphragm tension chamber which is in communication with the tension chamber 18 through the passage 34, as seen clearly in Fig. 2.

15 35 is a port affording communication between the tension chamber 33 and the chamber 12 through the passages 14 and 13, as clearly shown in Fig. 2.

36 is an extension of the passage 14.

20 37 is a button or abutment in contact with the diaphragm 32, being carried by the stem 38, as seen in Fig. 2, which is guided through an opening in the partition 39, 40 being a spring interposed between said partition and 25 the button or abutment 37.

41 is a valve carried by the stem 38 adapted to a valve seat 42 and closing a port 43 in communication with the tension chamber 36 and designed also to control the normally 30 open port 44, which is open to the atmosphere through the passage 3 between the stationary member of the pneumatic and the bottom of the valve chest. The valve stem is guided at its lower end in a suitable 35 guide 45.

51 is a bleed in the punching 54, as seen clearly in Fig. 2.

Upon reference to Fig. 2, it will be seen that the primary valve board 52 contains 40 the diaphragm chamber 31, the passage 48 communicating therewith and the port communicating with said passage and controlled by the primary valves. This board is removable so that access may be had to the 45 diaphragm and the valves carried by said board. The bottom board 53 of the valve chest carries the diaphragm 20 and contains the diaphragm chamber 21 and the secondary valve port, so that when said bottom board 50 is removed, access is had to said diaphragm and the said valve. The remaining parts of the valve chest are carried by the intermediate member 54 in which the 55 passages 14 and 49 are formed. This provides a small and convenient form of construction, permitting of ready access to any of the parts when desired. These parts, in practice, are generally united by screws as shown at 55 in Fig. 1, although glue may be 60 employed.

The tension chest is provided with a ledge 56, as seen in Figs. 1 and 2, on which the adjacent edges of the valve chests rest. A strip 57 is provided at the outer end of the 65 pneumatic upon which the valve chests rest,

as seen in Fig. 2, so as to maintain the same in proper relation and provide the intermediate space 3 hereinbefore referred to.

The operation is as follows: The atmospheric air, entering the perforations in the tracker bar, is conducted through the tubes 22 into the diaphragm chamber 21, thereby lifting the abutment 26, closing the port 46 and displacing the valve 29, so as to admit atmospheric air through the port 47 into the passage 48 which communicates with the diaphragm chamber 31 acting upon the diaphragm 32 and pressing the abutment 37 against the tension of the spring 40, moving the valve 41 to close the port 44 and open the port 43, thus opening communication between the pneumatic 1, through the passages 16, 15, and 49, valve chamber 50, port 43, passages 14 and 13, with the chamber 12 of the tension chest. This collapses the pneumatic and sounds the note. The note sheet, closing the opening in the tracker bar, shuts off admission of air through the tube 22 to the diaphragm chamber 21 and the parts are automatically returned to their normal position, the bleed 51 permitting this action.

Modifications in detail may be resorted to without departing from the spirit of the invention or sacrificing any of its advantages.

What is claimed as new is:—

1. A tension chest, a power pneumatic secured thereto, extended beyond the same to form an angle with a wall of said chest and a valve chest secured to the tension chest independently of the pneumatic and disposed in said angle, the wall of the tension chest adjacent the wall of the valve chest having independent passages one affording communication between the tension chest and an opening to the interior of the valve chest, and the other affording communication between the valve chest and an opening to the pneumatic.

2. A tension chest, a power pneumatic secured thereto, and a valve chest secured to the tension chest independently of the pneumatic, said pneumatic extending beyond the tension chest and partly supporting the valve chest the wall of the tension chest adjacent the wall of the valve chest having independent passages connecting both the tension chest and an opening to the pneumatic with the valve chest, one of said passages including a vertical passage in a 110 wall of the tension chest.

3. A tension chest, a power pneumatic secured thereto, and a valve chest secured to the tension chest, there being passages in the wall of the tension chest connecting both 125 the tension chest and the pneumatic with the valve chest there being a space intermediate the pneumatic and valve chest communicating with the atmosphere and communicating with the pneumatic.

4. A tension chest, a power pneumatic secured thereto and a valve chest secured to the tension chest, there being passages connecting both the tension chest and the pneumatic with the valve chest, there being also a space intermediate the pneumatic and the valve chest communicating with the atmosphere and communicating with an opening leading to the pneumatic, one passage 10 communicating with the pneumatic, the valve chest having a passage registering with the other of said passages, said tension chest being provided with a ledge on which the adjacent edge of the valve chest rests.
- 15 5. A tension chest, a plurality of pneumatics secured thereto and a plurality of valve chests, each chest having a shoulder intermediate its length upon each side, and means readily removable from the tension chest 20 and interposed between each two chests and engaging the shoulders of adjacent chests, and means connecting said means with the tension chest to secure the valve chests to the tension chest independently of the pneumatics.
- 25 6. A tension chest, a plurality of pneumatics secured beneath the same, a plurality of valve chests supported at one end on the tension chest independently of the pneumatics, and means readily removable from the tension chest and bearing conjointly upon two adjacent valve chests between the same intermediate their length to secure the valve chests to the tension chest independently of the pneumatics.
- 30 7. A valve chest comprising outer parts, each containing a diaphragm chamber, diaphragms therefor, a part intermediate said parts and having a plurality of chambers in 35 its opposite faces, and an intermediate channel one of the chambers on each face being opposed to the diaphragm chamber of the adjacent outer part, the other chambers forming valve chambers, one of said outer
- parts having means for connection with a tracker bar and the other a port and a valve controlling said port.
8. A valve chest comprising separable parts, an intermediate unitary part thereof having a plurality of chambers in its opposite faces, the chambers on one face being opposite to those on the other, a valve in one of said chambers, a diaphragm abutment in the other, a channel in said intermediate part, a port leading from the diaphragm chamber to said channel, and an auxiliary tension passage having communication through said channel with the tension chest.
9. A tension chest, a plurality of pneumatics on which said tension chest rests, a plurality of valve chests one for each pneumatic and each having communication with its pneumatic and with the tension chest, and means interposed between adjacent 65 valve chests and connected with the tension chest and overlapping adjacent pneumatics to secure the valve chests to the tension chest independent of the pneumatics.
10. A plurality of pneumatics, a tension 70 chest common thereto, a plurality of valve chests one for each pneumatic having communication each with its pneumatic and with the tension chest with a space between each valve chest and its pneumatic communicating with the atmosphere and with the pneumatic, and means acting conjointly upon two adjacent valve chests intermediate their lengths and securing the same to the tension chest independent of the pneumatics.

Signed by me at Washington, D. C., this 10th day of March 1910.

GEORGE P. BRAND.
